CARL RICHARD WALLER AND PER ARVID PETERSON, OF TRENTON, NEW JERSEY,
ASSIGNORS TO DE LAVAL STEAM TURBINE COMPANY, OF NEW YORK, N. Y., A
CORPORATION OF NEW JERSEY.

GOVERNING MECHANISM FOR FLUID-PRESSURE TURBINES.

1,183,921.

Specification of Letters Patent.

Patented May 23, 1916.

Application filed February 17, 1913. Serial No. 748,880.

To all whom it may concern:

Be it known that we, CARL RICHARD WALLER, a citizen of the United States, and PER ARVID PETERSON, a subject of the King of Sweden, both residents of Trenton, in the county of Mercer and State of New Jersey, have invented certain new and useful Improvements in Governing Mechanism for Fluid-Pressure Turbines, of which the following is a specification.

Our invention relates to improvements in governing mechanism for fluid-pressure turbines, particularly steam turbines, and comprises fluid-pressure-operated, governor-controlled means for operating a plurality of structurally separate valves and for operating such valves in succession; that is to say, for opening the valves one after another, in a predetermined order, and for closing them in reverse order.

Other features of our invention will be pointed out hereafter.

The objects of our invention are to improve and simplify governing mechanism of fluid-pressure motors generally, and particularly of steam turbines, to render the governing mechanism readily adaptable to motors of widely different designs, to provide simple mechanism for opening and closing a plurality of valves in succession, to provide means whereby a single governor may control the movements of such valves with a minimum of work done by the governor itself, to avoid the use of auxiliary devices for holding one or more of the valves open during the starting up of the motor, and generally to make the governing and valve operating mechanism simple, easy to manufacture, easy to maintain, sensitive and reliable.

We will now proceed to describe our invention with reference to the accompanying drawings, illustrating, more or less diagrammatically, mechanism embodying our invention, and will then point out the novel features in claims.

In the drawings: Figure 1 shows diagrammatically and in part in elevation and in part in vertical section, a governing mechanism embodying our invention and comprising two valves arranged to be opened and closed successively. Fig. 2 is a plan view of the levers shown in Fig. 1.

Fig. 3 is a diagrammatic elevation and partial section showing the control of three valves in accordance with our invention, two of the valves being shown open and one closed. Fig. 4 shows a plan view of the parts shown in Fig. 3. Fig. 5 is a view similar to Fig. 3, but showing one only of the valves open.

In mixed pressure turbines, particularly turbines in which the low pressure stage is intended to be operated by the exhaust steam of a reciprocating engine, or by other steam which is to be regarded, relatively, as waste steam, it is usually sought to carry as large a proportion of the load as possible by such low pressure, or, relatively speaking, waste, steam, high pressure steam being admitted only at such times and in such quantities as may be necessary to carry the load on the turbine, and to maintain the desired speed of the turbine. The arrangement shown in Fig. 1 is designed to operate in this manner.

In Fig. 1, numeral 1 designates the casing of a low pressure valve and numeral 2 the casing of a high pressure valve. 3 designates the inlet chamber and 4 the outlet chamber of the low pressure valve, and 5 the inlet chamber and 6 the outlet chamber of the high pressure valve. The valves proper, of which 7 is the low pressure valve and 8 the high pressure valve, are double balanced puppet valves, the low pressure valve, 7, opening downward for a reason to be explained hereafter, while the high pressure valve, 8, opens upward, in the particular arrangement shown. 12 designates a suitable centrifugal governor for controlling the operation of the valves in the manner hereinafter described. The stem 14 of the low pressure valve 7 is suitably guided and is provided at its upper end with a piston 95 working in a pressure cylinder 16 mounted upon the bonnet 17 of the valve casing 1. The stem 18 of the high pressure valve 8 is similarly guided and is provided at its upper end with a piston 19 working within a pressure cylinder 20 mounted on the top of the bonnet 21 of the high pressure valve casing. Similar pilot valves 22 and 23 supply fluid under pressure to these pressure cylinders, 16 and 20 respectively, for the operation of valves 7 and 8. These pilot

valves in the construction shown, are of the piston type. Pilot valve 22 comprises four valve pistons, 24, 25, 26 and 27, controlling the flow from supply pipe 28 to one or the other of pipes 29 and 30 leading to the lower and upper sides of pressure cylinder 16 respectively, and controlling the discharge of fluid from the cylinder 16 through pipes 29 and 30. Such pilot valves being well known, it is considered unnecessary to describe the pilot valve in detail. Pilot valve 23 comprises a similar arrangement of valve pistons controlling the supply of fluid under pressure from supply pipe 31 to either of the two pipes 32 and 33 leading to the lower and upper sides of pressure cylinder 20, respectively. For operating these pilot valves, governor 12 has connected to it a lever 34 pivotally connected at 35 to another lever 36 connected at 37 to the stem 14 of the low pressure valve 7; lever 36 having a fulcrum at 38, and the stem 39 of pilot valve 22 being pivotally connected to lever 34 at 40. Governor 12 has also connected to it a lever 41 having a fulcrum at 42 and pivoted at 43 to a lever 44 to one end of which the stem 45 of the pilot valve 23 is pivotally connected at 46; while the other end of said lever 44 is pivotally connected to the stem 18 of the valve 8 at 47.

In Fig. 1 the pilot valves are shown in positions which they would occupy when the turbine which they control, and which drives the governor 12, is in operation, these pilot valves being in such position that the low pressure valve 7 is wide open and that, with any momentary decrease in speed of the governor 12, the valve pistons connected to the stem 45 of pilot valve 23 will open communication between supply pipe 31 and pipe 32 and will open pipe 33 to discharge, so causing piston 19 to open valve 8. Similarly, if the speed of the governor should rise slightly, the valve pistons of the pilot valve 22 will be raised, to an extent sufficient to connect pipes 28 and 29, and to connect pipe 30 to discharge, so causing piston 15 to rise slightly and partly close valve 7. Owing to the connection of lever 36 to valve stem 14, and to the connection of lever 44 to valve stem 18, any movement of one of the pilot valves such as causes the corresponding main-valve-operating piston to move, results in the immediate return of that pilot valve to closed position, unless the governor be still changing the position of the corresponding lever, 34 or 40. Consequently the mechanism shown is capable, not merely of closing and opening the valves 7 and 8, but of making intermediate closed adjustments of said valves. The valve pistons of the two pilot valves have room for such over-travel that pilot valve 23 does not cause the high pressure valve 8 to open until valve 7 is wide open, or nearly so; and correspondingly

that, upon decrease of load, valve 8 is closed completely before any material closing of valve 7 begins.

When low pressure main valve 7 is opened to an extent to supply low pressure steam to practically the maximum extent possible under the then existing circumstances to the turbine, and the governor 12 causes the high pressure main valves 8 to open, such opening of the main valves 8 may be accompanied by further motion of the low pressure main valves 7 in the direction of opening (which further motion of the main valve 7 will not, however, under such conditions, cause any further increase in rate of flow of the low pressure steam) in which case there will be no corresponding over-travel of the low pressure pilot valve 22, since the motion of the main valve 7, transmitted through the "follow up" connections 36-35-34 to the low pressure pilot valve 22 will preclude such over-travel of pilot valve 22; or, alternatively, the low pressure main valves 7 may be arrested in their wide open position, by means of a stop 7^a, in which event as the valves 8 open the low pressure pilot valve 22 will over-travel without, of course, any effect on the low pressure main valves 7. Both arrangements are practical.

As previously stated, valve 7 opens by a downward movement. The reason for this arrangement of said valve is as follows: Pressure is usually maintained in the supply pipes 28 and 31, leading to the pilot valves, by a suitable pump driven by the turbine or other motor which the main valves 7 and 8 control. Since this pump will not produce any material pressure in the pipes 28 and 31, when the turbine or other motor is at rest, or until such turbine or other motor has begun to turn over at considerable speed, if the valve 7 opened upward it would be necessary to provide auxiliary means for imparting pressure to the fluid in pipe 28 to open said valve 7 for starting, or else to provide other means for raising said valve 7 and holding it open until the pump had reached a speed sufficient to produce the pressure in pipe 28 required to open said valve 7 still farther or to hold it open. But with the valve 7 arranged to open downwardly as shown, such valve will be open normally when the motor is at rest and when such motor is being started, and valve 7 will be closed only when, through slight excess of speed, the governor 12 operates to close it.

The governing arrangement shown in Fig. 1, besides being applicable to mixed pressure turbines, is applicable to multistage turbines in which steam or other working fluid is supplied, normally, by one valve, 7 for example, to the highest pressure stage, and live steam is admitted through another valve, 8 for example, to an intermediate stage, when this is required by overload con-

ditions. The supply of live steam to an intermediate stage to take care of overloads is in itself well known, and therefore we do not deem it necessary to illustrate particularly the application of the governing mechanism of Fig. 1 for such use, but merely mention the fact that the governing mechanism shown is applicable to such use, in order that it will be understood that it is not essential that valve 7 control steam of one pressure and valve 8 control steam of another pressure. Both valves may control steam of the same pressure.

The governing mechanism embodying our invention is also applicable to the control of more than two valves. This is illustrated in Figs. 3, 4, and 5, wherein numeral 12 designates, as in Fig. 1, a suitable governor, numerals 48, 49 and 50 designate valves to be controlled by that governor, numerals 51, 52 and 53 designate suitable fluid pressure motors (cylinders and pistons) for adjusting said valves 48, 49 and 50, respectively, and numerals 54, 55 and 56 designate suitable pilot valves for controlling the motors 51, 52 and 53, respectively. The pistons of these motors 51, 52 and 53 are connected, respectively, to levers 57, 58 and 59 to which the stems of the several pilot valves are also connected, and said levers 57, 58 and 59 are connected to a lever 60 operated by the governor 12 in such manner that when lever 16 moves, in one direction or another, the levers 57, 58 and 59, all move; but the positions of the pilot valves with respect to said levers 57, 58 and 59 are such that, starting with all the main valves closed, movement of the governor lever 60 operates pilot valve 54 to open valve 48 first, and further movement of the governor lever is required to open valve 49, and still further movement of the governor lever is required to open valve 50.

61, in Fig. 1, designates a dash pot connected to a projecting portion of lever 41 and serving to make the motions of the pilot valves and governor somewhat gradual, so avoiding too sudden changes of speed or valve adjustment. The construction of these dash pots is well known and therefore it has not been deemed necessary to illustrate the internal construction thereof.

What we claim is:—

1. A governing mechanism for fluid-pressure motors comprising a single speed governor, a plurality of main valves to be adjusted thereby, and each provided with a fluid-pressure motor for operating it, separate pilot valves for said valve-operating motors, and levers connecting said governor to said pilot valves and to the main valves, such levers arranged to restore each pilot valve upon the movement of the corresponding main valve resulting from a governor-caused movement of such pilot valve, the pilot valves arranged, one for over-travel

while its main valve is closed, another for over-travel after its main valve is well open, whereby one of said main valves does not open until the other main valve is well open, and closes before such other main valve 70 closes.

2. A governing mechanism for fluid-pressure motors comprising in combination a single governor, a plurality of main valves, each provided with a fluid-pressure motor 75 for operating it, separate pilot valves for said fluid-pressure motors and levers connecting said governor to said pilot valves and to said main valves, the connections being such that each pilot valve is restored 80 upon movement of the corresponding main valve consequent upon governor-caused movement of the corresponding pilot valve, and that one of said main valves opens after the other main valve is well open and closes 85 before such other main valve closes, that main valve which opens first being acted upon normally by a force tending to hold it in open position, whereby such valve will be open when its corresponding valve-actuating motor is not holding it in closed position.

3. A governing mechanism for fluid pressure motors comprising a single speed governor, two main valves to be adjusted thereby, and each provided with a fluid-pressure-motor for operating it, separate pilot valves for said valve-operating motors, two levers for connecting the governor to one of said pilot valves, such levers pivotally connected 95 to each other and one connected to the governor and pivoted at a fixed point, the other connected to said pilot valve and to the main valve controlled by that pilot valve, and two other levers for connecting the governor to the other said pilot valve, such last mentioned levers pivotally connected to each other, and one of them being connected to the governor and to the corresponding pilot valve, the other being pivoted at a fixed 100 point and connected to the main valve controlled by that pilot valve.

4. A governing mechanism for fluid-pressure motors comprising a single speed governor, two main valves to be adjusted thereby, and each provided with a fluid-pressure motor for operating it, separate pilot valves for said valve-operating motors, two levers for connecting the governor to one of said pilot valves, such levers pivotally connected 115 to each other and one connected to the governor and pivoted at a fixed point, the other connected to said pilot valve and to the main valve controlled by that pilot valve, a dash pot connected to the first of said two 120 levers, and two other levers for connecting the governor to the other said pilot valve, such last mentioned levers pivotally connected to each other, and one of them being connected to the governor and to the corre- 130

sponding pilot valve, the other being pivoted at a fixed point and connected to the main valve controlled by that pilot valve.

5. A governing mechanism for fluid-pressure motors comprising a single speed governor, two main valves to be adjusted thereby, and each provided with a fluid-pressure motor for operating it, separate pilot valves for said valve-operating motors, two levers 10 for connecting the governor to one of said pilot valves, such levers pivotally connected to each other and one connected to the governor and pivoted at a fixed point, the other connected to said pilot valve and to the 15 main valve controlled by that pilot valve, and two other levers for connecting the governor to the other said pilot valve, such last mentioned levers pivotally connected to each other, and one of them being connected to 20 the governor and to the corresponding pilot valve, the other being pivoted at a fixed point and connected to the main valve controlled by that pilot valve, the first of such main valves being arranged to open upward, 25 and the second of such main valves being arranged to open downward.

6. A governing mechanism for fluid pressure motors, comprising a single speed governor, a plurality of main valves to be adjusted thereby, and each provided with a fluid-pressure motor for operating it, separate pilot valves for said valve-operating motors, and means, including follow-up 30 means, connecting said governor to said pilot valves and to the main valves, such con-

necting means arranged to restore each pilot valve upon the movement of the corresponding main valve resulting from a governor-caused movement of such pilot valve, one of such pilot valves arranged for over-travel 40 after its corresponding main valve has reached its limit of intended movement and while the other main valve is in position for adjustment by the governor.

7. A governing mechanism for fluid pressure 45 motors comprising a single speed governor, high pressure and low pressure main valves to be adjusted thereby, and each provided with a fluid-pressure motor for operating it, separate pilot valves for said valve-operating motors, means, including follow-up means, connecting said governor to said pilot valves and to the main valves, such connecting means arranged to restore each pilot valve upon the movement of the corresponding main valve resulting from a governor-caused movement of such pilot valve, the high pressure pilot valve arranged for over-travel while the high pressure main valve is closed, and while the low 50 pressure main valve is in position for adjustment by the governor:

In testimony whereof we have signed this specification in the presence of two subscribing witnesses.
